Patented Sept. 21, 1926.

UNITED STATES PATENT OFFICE.

JOHN OLIPHANT, OF CHICAGO, ILLINOIS, ASSIGNOR TO SULLIVAN MACHINERY COMPANY, A CORPORATION OF MASSACHUSETTS.

PUMPING SYSTEM.

Application filed November 3, 1921. Serial No. 512,602.

My invention relates to pumping systems and more particularly to pumping systems of the displacement type.

An object of my invention is to provide an improved pumping system. Another object of my invention is to provide an improved pumping system of the displacement type. A further object of my invention is to provide an improved pumping system of the so-called displacement type especially adapted for use in wells of great depth. Other objects and advantages of my invention will appear in the course of the following specification and appended claims.

In the accompanying drawings, I have shown for purposes of illustration, one form which my invention may assume in practice.

In these drawings,

Fig. 1 is a view in elevation partially broken away of my improved pumping system installed in a well.

Fig. 2 is a central vertical section through a number of stages thereof.

Fig. 3 is a transverse section on a plane corresponding to the line 3—3 of Fig. 2.

Fig. 4 is a section on a plane corresponding to the line 4—4 of Fig. 6 and showing the valve in intermediate position.

Fig. 5 is an elevation of one form of controlling mechanism which may be employed with my pumping mechanism.

Fig. 6 is a view likewise in elevation of the same mechanism, the view showing the parts as if the entire mechanism were turned bodily about a vertical axis through 90 degrees.

Fig. 7 is a plan view of the mechanism

shown in elevation in Fig. 5.

Fig. 8 is a vertical section taken on the broken line 8—8 of Fig. 7.

Fig. 9 is a detail of the automatic air inlet valve hereinafter described.

In its illustrative form my invention comprises a series of displacement chambers arranged one above the other and formed of a series of pipe sections secured between and connecting a number of intermediate separating members. The several displacement chambers which are designated respectively 1, 2, 3 and 4, are arranged in a well casing 5 and the lowest member 1 is completely submerged as indicated at 6. As the general details of construction of the several displacement chambers are the same, I will de-

scribe but one, selecting for my purpose the bottom chamber. This comprises a cylindrical member 7 which is closed at its lower end by a head member 8 traversed by a vertically extending passage 9 which is closed at its top by a ball check valve 10 which may be unseated by inflowing liquid but which prevents the discharge of liquid therefrom. A discharge pipe 11 extends from an upper head member 12 almost to the bottom of the chamber and is provided upon the head member 12, but in the next succeeding chamber 2 with a ball discharge check valve 13 controlling a passage 14 which is a continuation of the discharge pipe 11. This valve serves as the inlet valve of the next higher chamber. A passage 15 permits the entry of a gaseous fluid which is used to force the liquid from the chamber. It will be understood that the chambers 2, 3 and 4 are generally similar to the chamber 1, differing therefrom, in fact, only in that the bottom heads of these chambers contain in addition to the inlet check valve, a passage corresponding to the passage 15. For the purpose of supplying pressure fluid to the several chambers to effect the discharge of the liquid therefrom I arrange a pair of fluid pressure conducting pipes 16 and 17, and of these pipes, pipe 16 supplies pressure simultaneously through the ports 15 to, say, the first, third, and as many other odd numbered chambers as there are, counting from the top of the well, while the pipe 17 supplies pressure to the passages 15 in all the even numbered chambers, counting from the top of the well. For example, it will be noted that the pipe 16 is supplying pressure to chambers 4 and 2 which are respectively the first and third chambers from the top of the well, while pipe 17 will supply pressure to chambers 3 and 1, respectively the second and fourth from the top of the well. As it will be evident that I do not intend to use invariably four chambers, but may use any number of chambers depending upon the depth of the well from which material is to be pumped, it will be understood that other chambers may be arranged at the top and bottom of the well and that additional connections between the pipe 16 or 17 and these chambers can be made. As it will be further evident that in a deep well changes in

pressure are transmitted much more slowly at opposite sides as indicated at 32 and 33 in such manner that in opposite positions of the valve it may connect ports 30 and 29 and 28 and 31, or vice versa.

For the purpose of controlling the movements of the valve 27 I employ a control mechanism which is the invention of one David H. Hunter and which serves to automatically reverse the position of the valve 27 at suitable intervals. This mechanism which is generally designated 50 comprises a pair of cylinders 51 and 52 of which the cylinder 51 is an operating cylinder and the cylinder 52 a dashpot cylinder. Within the cylinder 51 is reciprocable a piston 53 to whose upper end is attached an L-shaped crosshead 54 and which carries above the crosshead a weight 55. Air may be supplied to the cylinder 51 by way of a port 56 from a pipe 57 controlled by an ordinary three-way valve 58, hereinafter referred to more in detail. Within the cylinder 52 is reciprocable a dashpot piston 59 connected by a rod 60 with the crosshead 54 whereby the dashpot piston 59 and the actuating piston 53 move simultaneously, the rate of movement of the actuating piston 53 being governed by the rate of possible movement of the dashpot piston 59. To control the movements of the dashpot piston 59 there is arranged in the wall of the cylinder 52 a longitudinally extending port 61 which communicates with the interior of the cylinder by four ports, one arranged near the upper end of the cylinder and designated 62, one arranged substantially at the bottom and designated 63, and a pair near the middle of the cylinder separated by a short distance longitudinally of the cylinder, and respectively designated 64 and 65. An adjustable throttling screw 66 is arranged in the portion of the passage 61 which lies between the ports 64 and 65. It will be evident that the piston 59 may move rapidly on its upward travel until the port 65 is covered and must then move slowly as the liquid, herein oil, contained in the dashpot must be forced through the port 64 and around past the throttling screw 66 and through the port 65 until after the port 64 is passed and uncovered by the bottom of the piston and that thereafter the piston 59 may move rapidly, simply by passing the oil through the port 62, passage 61 and port 64. It will be evident that also on the downward movement of the piston 59 it will move rapidly adjacent each end of its travel and be retarded at the middle of its travel. The three-way valve 58 previously referred to is adapted to control the communication of a connection 67 leading from the compressor, with the port 56 and in one position of said valve opens free communication between the line 67 and the port 56, while in another position it interrupts such communication

and connects the port 56 with the atmosphere. As the construction of such valve is well known, no illustration is believed necessary, the ordinary T port, three-way valve being entirely satisfactory for this function. To control the movements of the valve 58 I have attached thereto an operating lever or arm 68 having oppositely extending arms, to one of which arms a spring 69 is attached, and the other of which arms is adapted to engage stops 70 and 71 formed on guides 72 and 73 in which an actuating rod 74 slides. To the rod 74 the spring 69 is attached at 75. The rod 74 is provided with adjustable collars or abutments 76 and 77 which are alternately engageable by the crosshead 54, through a hole in which the rod passes. It will be observed that as the rod 74 is raised to its upper position, the free end of the spring 75 will pass above the longitudinal axis of the arm 68 and that accordingly the valve 58 will be sharply reversed from the position shown in Fig. 6 to a position in which the supply of fluid to the port 56 will be cut off and the cylinder 51 vented. It will be noted that a similar mode of operation will occur upon the downward movement of the rod 74 and that accordingly the valve 58 has its position rapidly changed and that only at the ends of the travel of the crosshead 54. It will be noted that the valve 27 is provided with an operating arm 78 to which is pivoted an actuating rod 79 having collars 80 and 81 secured thereto and that the crosshead 54 also engages these collars by reason of the fact that the rod 79 passes through an opening in the crosshead 54.

The mode of operation of this mechanism will be readily apparent. Assume the control valve 58 to be in the position shown. Fluid under pressure passing from the line 67 through the valve 24, line 57 and port 56 beneath the piston 53 will force the latter upward, the rate of upward movement being controlled by the possible rate of movement of the dashpot piston 59. When the piston 53 has moved upward to a sufficient extent the crosshead 54 will engage the collar 81 and reverse the position of the valve 27. The crosshead 54 will likewise engage the collar 77 and at the extreme upper end of the desired movement the piston 53 will cause the reversing of the position of the valve 58. This will result in the downward movement of the piston 53 under the action of gravity due to its own weight and the weight 55, and the crosshead 54 near the lower end of its movement will shift the valve 27 in the opposite direction and will again shift the three-way valve 58 at the extreme end of its travel. It will be evident therefore that the valve 27 is moved relatively rapidly and that the movement of the piston is so controlled by the dash-

pot that the valve 27 is maintained stationary during practically the entire period of fluid pressure supply to the pipes 23.

For the purpose of permitting the supply of sufficient air to the compressor to fill one-half of the tanks with air at a pressure requisite to discharge the liquid, I have provided an automatic inlet valve 82 which valve, as best shown in Fig. 9, comprises simply an inwardly opening valve proper 83 normally held upon its seat 84 by a spring 85 but operative to be opened by atmospheric pressure when the pressure in the compressor intake falls substantially below atmospheric and to admit air to the suction line of the compressor. This valve operates during the starting of the system and thereafter opens only to admit air lost by leakage or by absorption in the water, etc. Means may be provided, as shown at 86, for positively raising the valve 83 from its seat during the starting period of the system.

The mode of operation of my improved mechanism is as follows: Assume that the control mechanism occupies the position shown in Figures 1 and 5 (which is the position which it will always occupy when the system is shut down) and that the compressor 22 is started. It will be understood that the cylinder 1 will be initially filled with liquid as it is so disposed as to be substantially submerged during normal pumping operation. The valve 83 will be opened wide before the compressor is set in operation so as to allow the compressor to have a free suction from the atmosphere and to reduce the flow of air through pipe 17, cylinder 3, cylinder 4 and pipe 16, it being evident that if pipe 16 were connected to the suction side of the compressor in such manner that there was a heavy suction thereon the pressure in pipe 17 would be much decreased and might, in fact, be so low in the portion below the valve 19 as to render starting very difficult. The operation of the compressor will cause the fluid entering the pipe 17 to exert a pressure on the surface of the liquid in chamber 1 and will force it upward through pipe 11 and valve 13 into chamber 2. By the time the control mechanism reverses the position of the valve 27, the liquid level in chamber 2, depending on various conditions, may stand at a few inches above the lower end of its discharge pipe 11 or may fill the tank to a considerable degree. When the valve 27 reverses, as stated, the pressure will be supplied through pipe 16 to tanks 2 and 4 while tanks 1 and 3 will be vented. Tank 1 will promptly refill by gravity and the liquid that was forced into tank 2 will be discharged into tank 3. When the valve 27 next changes position, water will be raised to tank 4, and so on until the entire system is in operation, it being evident that the filling of succes-

- sive tanks diminishes the possible points of leakage and that with the reduction of leakage there is an increase of the quantity of liquid which will enter the several tanks.
- 5 When the system is under operation sufficiently to begin discharging, the valve 83 is allowed to close and the operation of the system is speeded up due to the suction on the filling tanks. The valve 83 will there-
 10 after admit air automatically as needed to keep the system full, but will not open, due to its spring 85, unless the vacuum in the suction sides of the system is greater than a predetermined desired limit, which will
 15 be fixed by experiment for each system so as to secure the requisite pressure on the discharging tanks. It will be evident that the work of the compressor will be greatly reduced as, when the valve 27 reverses, the air
 20 under full compressor discharge pressure that has been forced into the discharged tanks will flow quickly through the compressor and equalize the pressure in both sides of the system and enable a considerable
 25 economy in power. To prevent loss of air during starting by escape through the final discharge pipe, the latter should be suitably loaded or closed during the starting period.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

- 40 1. In a pumping system, a plurality of serially arranged displacement chambers, means connecting the bottom of each of said chambers with the lower portion of that next prior to it, and means for supplying pressure to alternate ones of said chambers and suction to the remainder during substantially the entire respective periods of discharge and filling, and then reversing said supply and suction, said latter means being initially automatically controlled by an intermittent flow of fluid from said system.
- 45 2. In a pumping system, a series of superimposed displacement chambers, means for permitting discharge from each of said chambers to that next above it while preventing back flow, a fluid conducting means connected with every other one of said chambers, a fluid conducting means connected with the remaining intermediate chambers, means for permitting an adjustment of the connections between said conducting means and each of the chambers connected thereto, and means for alternately connecting said fluid conducting means with a source of pressure fluid and with a reduced pressure space.
- 50 3. In a pumping system, a series of superimposed displacement chambers, means for permitting discharge from each of said chambers to that next above it while preventing back flow, a fluid conducting means connected with every other one of said chambers, a fluid conducting means connected with the remaining intermediate chambers, means for adjusting the connection between each fluid conducting means and each of the chambers to which it is connected, means for alternately connecting said fluid conducting means with a source of pressure fluid and with a reduced pressure space, said last mentioned means being primarily controlled by an intermit-

tent flow of fluid from said system operating to supply pressure to the emptying tanks substantially throughout their period of discharge and to maintain a suction upon said filling tanks during an equal period.

4. In a pumping system, a series of superimposed displacement chambers, means for permitting discharge from each of said chambers to that next above it while preventing back flow, a fluid conducting means connected with every other one of said chambers, a fluid conducting means connected with the remaining intermediate chambers, the connections between each of said fluid conducting means and each of said chambers being valved, and means for alternately connecting said fluid conducting means with the suction and discharge sides of a compressor.

5. In a pumping system, a series of superimposed displacement chambers, means for permitting discharge from each of said chambers to that next above it while preventing back flow, a fluid conducting means connected with every other one of said chambers, a fluid conducting means connected with the remaining intermediate chambers, and means for alternately connecting said fluid conducting means with the suction and discharge sides of a compressor, said means being initially controlled by an intermittent flow of pressure fluid from said system and operating independently of the conditions in said chambers and operating to supply pressure fluid to the emptying tanks substantially throughout their period of discharge.

6. In a pumping system, a series of superimposed displacement chambers, means for permitting discharge from each of said chambers to that next above it while preventing back flow, a fluid conducting means connected with every other one of said chambers, a fluid conducting means connected with the remaining intermediate chambers, means for permitting an adjustment of the connections between said conducting means and each of the chambers connected thereto, and means for alternately connecting said fluid conducting means with a source of pressure fluid and with a reduced pressure space.

7. In a pumping system, a series of superimposed displacement chambers, means for permitting discharge from each of said chambers to that next above it while preventing back flow, a fluid conducting means connected with every other one of said chambers, a fluid conducting means connected with the remaining intermediate chambers, means for adjusting the connection between each fluid conducting means and each of the chambers to which it is connected, means for alternately connecting said fluid conducting means with a source of pressure fluid and with a reduced pressure space, and

means for permitting the admission of air to the suction side of such compressor from the atmosphere.

7. In a pumping system, a series of superimposed displacement chambers, means for permitting discharge from each of said chambers to that next above it while preventing back flow, a fluid conducting means connected with every other one of said chambers, a fluid conducting means connected with the remaining intermediate chambers, means for alternately connecting said fluid conducting means with a source of pressure fluid and with a reduced pressure space, and means for automatically permitting the admission of air to the suction side of such compressor from the atmosphere when a predetermined vacuum is reached, said means being manually controllable to effect a constantly open connection when desired.

8. A pumping mechanism comprising a displacement chamber adapted to be disposed within a well and having a fluid inlet port, and means disposed adjacent said inlet port for varying the supply of fluid thereto.

9. A pumping mechanism comprising a plurality of alternately operable displacement chambers adapted to be disposed within a well each having an inlet port for conducting fluid thereto, and means for varying the flow area of each of said inlets.

10. A pumping mechanism comprising a plurality of alternately operable displacement chambers adapted to be disposed within a well each having an inlet for supplying fluid thereto, and means for varying the flow area of each of said inlets to control the rate of discharge from said chambers independently of the pressure of the actuating fluid.

11. A pumping mechanism comprising a plurality of fluid displacement tanks each having an inlet, a common supply line for said tanks, and means for varying the flow of fluid from said line to each of said inlets.

12. A pumping mechanism comprising a displacement tank adapted to be disposed within a well and having an inlet, a supply pipe therefor, and an adjustable screw disposed adjacent said inlet for controlling the flow of fluid to said tank.

13. In a pumping system, a plurality of displacement tanks, and means whereby actuating fluid is delivered to each of the same at different pressures so as to insure that certain similar operations of said tanks will be substantially uniform.

14. In a pumping system, a plurality of displacement tanks, and means whereby actuating fluid is delivered to each of the same

at different pressures so as to insure that the length of time to discharge each of said tanks will be substantially the same.

15. In a pumping system, a plurality of displacement tanks, a single source of actuating fluid therefor, means for delivering actuating fluid from said source to each of said tanks, and means whereby said fluid is adapted to discharge the tanks substantially uniformly independently of varying pressure of the fluid delivered.

16. In a pumping system, a plurality of displacement tanks differently spaced from a source of actuating fluid, a single source of actuating fluid for said tanks, and means whereby actuating fluid from said source is delivered to each of said tanks at a pressure different from that at said source determined so as to insure that certain similar operations of said tanks will be substantially uniform.

17. In a pumping system, a plurality of superimposed displacement tanks adapted to be disposed within a well, means for supplying actuating fluid thereto, and means adapted to compensate for the decreasing pressure of the actuating fluid as it descends so as to insure that certain similar operations of said tanks will be substantially uniform.

18. In a pumping system, a plurality of superimposed displacement tanks adapted to be disposed within a well, pressure fluid conducting means associated therewith, the pressure of fluid therein being different at different points, and means adapted to compensate for the different pressures of said fluid so as to insure that certain similar operations of said tanks will be substantially uniform.

19. In a pumping system, a plurality of cooperating displacement tanks, a common pressure fluid supply pipe therefrom which said tanks successively draw actuating fluid so that said pressure fluid delivered to each of said tanks will be different, and means adapted to compensate for these different pressures so as to insure that certain similar operations of said tanks will be substantially uniform.

20. In a pumping system, a plurality of superimposed displacement tanks adapted to be disposed within a well, means for supplying actuating fluid thereto for discharging fluid therefrom, and means whereby the discharge from said tanks requires a substantially uniform length of time.

In testimony whereof I affix my signature.

JOHN OLIPHANT.
